MOTOR OPERATED KEY IDENTIFIER

Benjamin Cooper, Jersey City, N. J.

Application April 8, 1940, Serial No. 328,534

16 Claims. (Cl. 177—380)

This invention relates to motor operated key identifier. It is particularly directed to an identifier for use in registers, watchman systems, toll checking apparatus, and for the like purposes, and having a pulser actuated by a key to actuate printing counters, whereby a number may be printed corresponding to the shape of the key.

An object of this invention is to provide an identifier of the character described having highly improved means to print an identification of the key by means of a printing counter, when the key is inserted into the identifier and to again print zero on said counter when the key is withdrawn from the identifier.

A further object of this invention is to provide an identifier of the character described, operated by a key inserted into the identifier, the key having one or more shoulders and the positioning of the key in the identifier initiating movement of one or more segmental pulsers from an initial position into engagement with the shoulders of the key, so that said shoulders determine the extent of angular movement of the segmental pulsers, whereby the number of pulses on each pulser is proportionate to the extent of angular movement thereof, and hence depends upon the shape of the key.

Yet a further object of this invention is to provide an identifier of the character described, comprising pulsers and a motor to operate the pulsers, the operation of the motor being dependent upon the insertion of a key into the identifier, and the number of pulses caused by the pulsers depending upon the shape of the key inserted into the identifier, means being further provided to automatically stop the operation of the motor after the pulsers have pulsed and returned to their initial position.

A still further object of this invention is to provide in an identifier of the character described, pulser sectors, and pulsing contacts adapted to be actuated by the sectors, the angular extent of rotation of the pulsers being limited by a key positioned within the identifier, and means to automatically withdraw the contacts from the influence of the sectors after the pulsing operation is completed, and to permit the pulsing sectors to return to initial position.

Yet a further object of this invention is to provide a strong, rugged and compact identifier of the character described, which shall be relatively inexpensive to manufacture, comprised of comparatively few and simple parts, which shall

be smooth and positive in operation, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a rear elevational view of an identifier embodying the invention;

Fig. 2 is a side elevational view thereof;

Fig. 3 is a cross-sectional view taken on line 3—3 of Fig. 1;

Fig. 4 is a cross-sectional view taken on line 4—4 of Fig. 1;

Fig. 5 is a cross-sectional view taken on line 5—5 of Fig. 1;

Fig. 6 is a cross-sectional view taken on line 6—6 of Fig. 2;

Fig. 7 is an elevational, cross-sectional view of the friction drive between the motor and the train of gearing;

Fig. 8 is a perspective view of an identification key;

Fig. 9 is a cross-sectional view taken on line 9—9 of Fig. 3;

Fig. 10 is a cross-sectional view taken on line 10—10 of Fig. 3; and

Fig. 11 is a wiring diagram of the circuit controlling the identifier, the motor for operating the same, the electro-magnetic counters operated by the pulsers and the printer.

Referring now in detail to the drawings, 10 designates an identifier embodying the invention. The same comprises a front plate 11 formed with a circular opening 12, formed with a downwardly extending key-way 12a, and adapted to receive an identification key 13, to be described in detail hereinafter. Fixed to the rear surface of the wall 11, as by screws 14, are parallel horizontal studs 15 to which are fixed a pair of parallel rearwardly extending plates 16 and 17 interconnected at the rear by a pair of parallel studs 19.

Attached to the rear of plate 11 and extending rearwardly therefrom, is a tubular member 21. Tubular member 21 has a bore 22 adjacent the wall 11 of greater diameter than opening 12 and co-axial therewith. Rearwardly of the bore 22, tubular member 21 is formed with a bore 25 of substantially the same diameter as the opening

12. Fixed to the inside of tube 21, within bore 25, is a pin 25a aligned with the key slot 12a and projecting upwardly.

The end of the tubular member 21, adjacent the wall 11, is formed with a notch 26 at the top. The forward end of the tube 21 is also formed with a second notch or cut-away portion 27 having an angular extent of more than 90 degrees. Said tubular member 21 is furthermore formed with a vertical through opening 28 at the top, disposed rearwardly of the front wall 11 and formed with a counter-sunk shoulder 29. Said tubular member 21 is furthermore formed with a portion 30 of reduced outer diameter at its rear end, said portion 30 being formed with a slot 31 disposed in a plane parallel to the front wall 11 and substantially 90 degrees in extent, the same extending from the bottom of the tube to a horizontal plane passing through the axis of the tube. The forward end of tubular member 21 is formed with a shallow notch 21a, and fixed to said end, is a stop member 21b partially received within said notch and projecting radially inwardly.

Journalled within bore 22 of tubular member 21, is an annular ratchet ring 34 having a central opening 35 similar in diameter to the opening 12 in the front wall 11, and likewise formed with a key slot extension 35a adapted to register with the key slot 12a in said front wall 11. Said ring 34 is formed with a shallow depressed surface 36 having end shoulders 36a and 36b. The stop 21b projects into the depression 36 to limit angular movement of the ring 34. Thus, when the ring 34 is moved in a counter-clockwise direction, looking at Fig. 6, stop 21b will contact shoulder 36b to limit angular movement of the ring to 90 degrees, bringing the key slot 35a from the bottom to a position where it is horizontally aligned with the axis of said ring.

The outer periphery of the ring 34 is formed with a curved notch 38 spaced 90 degrees from the key slot 35a, going in a counter-clockwise direction from said key slot. Said ring 34 is also formed with ratchet teeth 39 at its periphery extending through an angle of somewhat more than 90 degrees in a clockwise direction from the key slot 35a.

The ring 34 is furthermore formed on the rear face thereof with a cut-away or groove 40 forming a thinned portion 41 carrying a pivot pin 42, on which is pivoted a pawl 43. Interposed between the pawl 43 and the bottom of the groove 40, is a spring 45 which normally projects the lower end of the pawl outwardly beyond the outer periphery of the ring 34, as shown in Fig. 6 of the drawings.

Rotatably mounted on the portion 30 of the fixed tubular member 21 is a sleeve 48 to which is fixed an inwardly projecting radial pin 49 extending within slot 31 of said tubular member. Slidably mounted within the opening 28 and tubular member 21, is a pin 50 of insulating material formed with a collar 51 adapted to be received within the counter-sunk opening 29. The lower end of pin 50 projects within the bore 25 when the collar 51 is in the counter-sunk opening 29, for the purpose hereinafter appearing.

Fixed to the rear of wall 11 is a bracket 52 carrying three spring fingers 53, 54 and 55, insulated from one another. The middle spring finger 54 is normally in contact with the finger 55 and out of engagement with the finger 53. When the pin 50 is lifted upon insertion of a key through the opening 12 and through the

tubular member 21, as will appear hereinafter, the pin 50 will be raised to move the spring finger 54 out of engagement with respect to spring finger 55 and into engagement with spring finger 53.

Pivoted to the rear surface of plate 11, as at 56, is an arm 57 carrying at its outer end an insulating button 58. Arm 57 traverses the slot 26. Within said slot is a roller 59 contacting the outer periphery of ring 34. On arm 57 is a projection 60 contacting the roller 59. When the ring 34 is rotated by the key 13 in the manner hereinafter explained, the roller 59 will drop into the notch 38 when the ring is rotated through an angle of 90 degrees. Fixed to the bracket 52 are a pair of spring contacts 64 and 65 normally held out of contact with one another by the button 58 on arm 57. However, when the ring 34 is rotated through an angle of 90 degrees, and arm 57 drops, said spring fingers come into contact with one another.

The key 13 will now be described:

Said key has a flat diametric handle 13a at its rear end and is formed at its forward end with a substantially cylindrical portion 13b of somewhat reduced diameter. At one end of the cylindrical portion 13b is an annular shoulder 13c. The cylindrical portion 13b is formed with a longitudinal slot 13d. Mediatly the ends of cylindrical portion 13b is a peripheral slot 13e communicating with the groove or slot 13d and extending to an angle of substantially 90 degrees. The outer end of the key 13 has two semi-circular shoulders 13f and 13g forming a flat surface 13h through the axis of the key. The groove 13d is in alignment with the lower edge of the flattened handle 13a and opens into one of the shoulders 13g. The flat surface 13h is perpendicular to the flattened handle 13a. Fixed to the key 13 is a radially outwardly projecting pin 13j in alignment with the groove 13d, and disposed rearwardly of the shoulder 13c.

As will be seen hereinafter, the key 13 will be identified by two numbers, one representing units and one representing tens. The linear positions of the shoulders 13f and 13g with respect to the axis of the key determines the identification of the key as these shoulders control a pair of pulsers which send pulses to a pair of electro-magnets M and M1, as will appear hereinafter.

The key is inserted into the opening 12 of the identifier with the handle 13a in vertical position, as shown in dot, dash lines in Fig. 3. The pin 13j thus passes through the key slot 12a into the key slot 35a of the ring 34. The pin 25a also passes into the groove 13d of the key. As the key is inserted, the pin 50 is lifted to move spring finger 54 out of engagement with spring contact 55 and into engagement with spring finger 53. The pin 49 on sleeve 48 is also received within the groove 13d of the key. When the key is fully inserted the pin 25a is aligned with the peripheral slot 13e of the key. The key is then turned in a counter-clockwise direction looking at Fig. 6 of the drawings, causing the ring 34 and the sleeve 48 to be rotated through an angle of 90 degrees. When the ring 34 has rotated through an angle of 90 degrees, stop 21b contacts shoulder 36b and roller 59 drops into notch 38 to permit arm 57 to drop to open the switch fingers 64 and 65.

It will be noted that when the key is inserted the surface 13h is in a horizontal position, but when it is rotated through an angle of 90 degrees,

said surface is in a vertical position, so that the two shoulders 13f and 13g are side by side and one in a different plane from the other.

Means is provided to prevent the key from being turned back after it has been rotated through an angle of 90 degrees until a print is made of the identification of the key in a manner to be described hereinafter. To this end, there is pivoted on a pin 70 on the rear surface of plate 11, a lever 71 having arms 72 and 73. Arm 72 has a pointed portion contacting the periphery of ring 34 and adapted to engage the ratchet teeth 39. Arm 72 is held in engagement with the ring 34 by a coil tension spring 74 anchored at one end of the plate 11, as at 75, and attached at its other end to said arm. The teeth 39 are so shaped as to permit rotation of the ring 34 in a counter-clockwise direction only, when arm 72 is in engagement therewith.

Means is provided to cause two independent sets of pulses to actuate two electro-magnets, M and M₁, dependent upon the positions of the shoulders 13f and 13g of the key 13. To this end, there is journalled in the parallel plates 16 and 17, a transverse horizontal shaft 77, parallel to plate 11. Independently rotatably mounted on said shaft are a pair of sectors 78 and 79, one disposed in alignment with the shoulder 13g, and the other in alignment with the shoulder 13f of the key 13 placed in circular opening 12. The front curved edges of said sectors are formed with nine teeth 78a, 79a, respectively. Said sectors are formed with upwardly extending fingers 78b and 79b adapted to contact the shoulders 13g and 13f when the sectors are swung upwardly or in a clockwise direction, looking at Figs. 2 and 3 of the drawings. Thus, the position of the shoulders determines the extent of angular movement of the sectors, as after the fingers 78b and 79b contact said shoulders, the sectors cannot move any more.

The shoulders 13g and 13f on the key 13 are located to permit movement of the sectors 78 and 79 through angles equivalent to the angle of from one to nine teeth, or one or the other shoulders may be so positioned as to prevent any angular movement of the sectors.

The sectors 78 and 79 are adapted to actuate the pulsing switches 78c, 78d and 79c, 79d. Said switches comprise a pair of spring contacts mounted on insulating blocks on the cross bars 19. The switches are normally open, but are closed by action of the sectors on levers 80 and 81 pivoted on a transverse pin 83 supported by the plates 16 and 17. The levers 80 and 81 have pawls 80a and 81a engaging the teeth of the sectors, and said levers furthermore carry insulating buttons 80b and 81b contacting the spring fingers 78d and 79d. As the sectors swing upwardly, the teeth oscillate the levers 80 and 81 to close the switches a number of times equal to the number of teeth which pass the pawls 80a and 81a. The switches 78c, 78d and 79c, 79d control the electro-magnets M and M₁, as will appear hereinafter.

It will be noted that the pawls 80a and 81a prevent downward swinging of the sectors until said pawls are released in the manner hereinafter appearing.

Said levers 80 and 81 have downwardly extending arms 80c and 81c interconnected by springs 80d and 81d to the plates 16 and 17 to retain the pawls 80 and 81a in engagement with the toothed peripheries of the sectors.

Means is provided to rotate the sectors upwardly into engagement with the shoulders 13g and 13f automatically, upon inserting the key into the identifier and rotating the same through an angle of 90 degrees. To this end, there is mounted on plate 16, an electric motor 85, having an output shaft 86, journalled in plate 16. Mounted on the shaft 86 is a pinion 87 connected to said shaft through a usual friction drive 88. The pinion 87 is connected through a train of gearing 89 to a pinion 90 on a shaft 91 journalled in plate 17. On shaft 91 is a fixed cam 92. The direction of rotation of the motor is such that the shaft 91 will be rotated by said motor in a counterclockwise direction, looking at Fig. 4 of the drawings.

Pivoted on plate 17 is a lever 94 having arms 94a and 94b. Arm 94a is in contact with the cam 92. As said cam 92 rotates in a counterclockwise direction, lever 94 will be rotated in a clockwise direction, when the high part of the cam engages arm 94a of said lever. Journalled within plate 17, is a stud shaft 95. On one end of said shaft is an arm 95a engaging arm 94b of lever 94. At the other end of the shaft is a plate 95b contacting the arms 80c and 81c of the levers 80 and 81. Rotation of the lever 94 in a clockwise direction will rotate arm 95a in a counter-clockwise direction, to rotate the levers 80 and 81 in a counter-clockwise direction, to release pawls 80a and 81a from the teeth of the sectors 78 and 79, thus also closing the switches 78c, 78d and 79c, 79d.

On shaft 91 is a second cam 96 having a peripheral cam edge increasing in height through an angle of 180 degrees and then decreasing in height through the other angle of 180 degrees. The high part of the cam 92 is aligned with the portion of the cam 96 which decreases in height, for the purpose hereinafter appearing.

Rotatably mounted on shaft 77 are a pair of parallel arms 97 interconnected at their outer ends by a transverse rod 98. Said rod is interconnected to the fingers 78b and 79b of the sectors 78 and 79 by coil tension springs 99.

Rotatably mounted on the shaft 77, and fixed for rotation together with the arms 97, is a follower 101 carrying a roller 100 contacting the periphery of cam 96. The arms 97 are provided with fingers 102 connected by coil tension springs 103 to the fixed plates 16 and 17. The springs 103 tend to rotate arms 97 in a counter-clockwise direction. Said arms are interconnected by a second transverse bar 99a. The sectors 78 and 79 are formed with finger extensions 99b normally held in contact with the transverse bar 99a by the springs 99.

It will now be understood that as the motor operates the train of gearing, the cam 96 will rotate to lift the follower 101 or rotate the same in a clockwise direction, looking at Fig. 2 of the drawings, thus rotating the arms 97 and hence rotating the sectors 78 and 79 under the influence of the springs 99 until the fingers 78b and 79b contact the shoulders on the key 13. When the shoulders are contacted, rotation of the sectors stops but the follower may continue to rotate, thus tensioning the springs 99.

As the cam 96 continues to rotate, the follower begins to drop or rotate in a counter-clockwise direction, and since at that time, the levers 80 and 81 have been retracted, the sectors 78 and 79 will begin to rotate likewise in a counter-clockwise direction, back to initial position.

Since the switches 78c, 78d and 79c, 79d are

closed while the sectors return to initial position, means is provided to open the circuits for the magnets M and M_1 so that the magnet circuits will be open during this period. To this end, there is fixed to the shaft 91 , a cam 104 made of insulating material. Mounted on a bracket 105 fixed to the rear of the front plate 11 , are three spring fingers 106 , 107 and 108 . The spring finger 106 is normally in contact with the spring finger 107 , but just before the sectors 78 and 79 begin to come down, the high part of the cam lifts the middle finger 106 to break the contact between said spring finger and the finger 107 and to move the finger 106 into engagement with the finger 108 which controls the printing circuit which will appear hereinafter.

Means is provided to automatically start the operation of the motor, upon inserting the key and turning the key through an angle of 90 degrees. To this end, the motor 85 is controlled by the switch 64 , 65 which is normally open, but which closes when the key is inserted and rotated through an angle of 90 degrees, as described hereinabove. There is also disposed within the motor circuit, a pair of normally open spring fingers 110 and 111 .

Means is provided to close said spring fingers 110 and 111 automatically upon inserting the key and turning the same through an angle of 90 degrees, and for automatically opening said switch and releasing the ratchet ring 34 , after the cam 96 has been rotated through an angle of 360 degrees to permit rotation of the key back through an angle of 90 degrees, so that the key may be withdrawn. To this end, there is pivoted on a pin 115 on the rear surface of the plate 11 , a latch 116 . On latch 116 is a pin 117 located beneath the arm 73 of lever 71 . Pivoted at its upper end to the latch 116 , as at 119 , is a link 120 .

Carried by the plate 17 , is a plate 122 parallel thereto and having a bearing opening through which the shaft 91 passes. Pivoted to said plate 122 is a lever 123 having an arm 124 , to which the lower end of the link 120 is pivoted. Interconnecting the arm 124 of lever 123 with plate 17 , is a coil tension spring 125 which is inclined upwardly and toward the plate 17 . Lever 123 also has an arm 126 provided with a downwardly extending latch finger 127 and with an insulating projection 128 .

Mounted on shaft 91 is a disc 130 having a peripheral flange 131 on one side thereof. The flange 131 is formed with a cut-away 132 . The disc is furthermore formed with a socket 133 in its periphery, adjacent the cut-away portion 132 of the flange. Cut-away 132 begins near the leading end of socket 133 and extends beyond said socket. At the ends of cut-away 132 are shoulders $133a$, $133b$.

When the key is inserted into the identifier and rotated through an angle of 90 degrees, the pawl 43 on the ring 34 will contact the tip of the latch 116 and rotate the latter downwardly in a clockwise direction, looking at Fig. 6 of the drawings, to lower the link 120 to rotate the lever 123 in a clockwise direction, looking at Fig. 5 of the drawings. This action will lift the latch finger 127 from the socket 133 , and the spring finger 125 being inclined will tend to rock the lever 123 about a vertical axis passing through the pivot pin on which the lever 123 is mounted to bring the latch finger 127 onto the notched portion 132 of the rim of the flange 131 , adjacent shoulder $133a$. As the motor rotates, the finger 127 will ride on notched rim portion 132 until it strikes

shoulder $133b$ and is transferred to the periphery of the disc 130 beyond socket 133 .

As the lever 123 rotates in a clockwise direction, button 128 closes the normally open spring fingers 110 and 111 , thus closing the motor circuit and starting the operation of the motor. When the motor has rotated shaft 91 to through an angle of 360 degrees, latch finger 127 will drop into the notch or socket 133 to stop rotation of said shaft, automatically, and to open the switch 110 , 111 to stop the operation of the motor. The motor may continue to rotate through inertia by reason of the friction drive between the shaft 86 and the pinion 87 . Furthermore, as the lever 123 rotates in a counter-clockwise direction to stop the operation of the motor and the shaft 91 , rod 120 will be lifted to raise the latch 116 and rotate the lever 71 in a clockwise direction about pivot 70 , looking at Fig. 6 of the drawings, to release arm 72 from the ratchet teeth 39 , thus permitting the key to be rotated back to its initial position through an angle of 90 degrees, whereby the key may be withdrawn from the identifier.

Means is provided to print by means of the counter wheels associated with the counters M and M_1 automatically after the pulsing operation, to record an identification of the key, to automatically reset or zeroize the counter wheels after the printing operation, and to print a second time against said counter wheels upon withdrawing the key from the identifier. To this end, there is provided a printing solenoid 140 adapted to operate a printing platen 141 , to move said platen upwardly against the counter wheels 142 and 143 , paper and printing ribbon being interposed between the platen and the counter wheels in the usual manner, to cause a print on the paper. The solenoid 140 is provided with a coil 144 connected at one end to a minus power supply. The coil is connected by wire 145 to a fixed contact 146 . A switch arm $147a$ connected to a plus power supply is normally spaced from the fixed contact 146 , but is adapted to be moved into engagement therewith by a relay 147 . The coil 148 of the relay 147 is connected at one end to a plus power supply and at the other end to a switch arm 149 . Switch arm 149 is normally in engagement with a fixed contact 150 , and spaced from a second fixed contact 151 .

The switch arm 149 is moved out of engagement with respect to contact 150 and into engagement with contact 151 by relay 152 . Said relay is adapted to move a switch arm 153 normally in engagement with a fixed contact 154 to open position when said relay is energized. Said relay, furthermore, is adapted to move switch arms 155 , 156 and 157 into engagement with fixed contacts 159 , 160 and 161 . Fixed contact 154 is connected by wire $154a$ to spring finger 106 . Fixed contact 150 is connected by wire $150a$ with the spring finger 108 . Fixed contact 151 is connected by wire $151a$ with spring finger 55 . Spring finger 54 is connected to a minus power supply. Spring finger 53 is connected by wire $53a$ to the switch arm 157 . The switch arms 155 and 156 are connected to a minus power supply.

The printing platen 141 is connected to a switch arm 163 connected by said wire $53a$ to the switch arm 157 . When the printing platen is in normal position, switch arm 163 is in engagement with a fixed contact 164 connected to a minus power supply. When the printing solenoid 140 is energized, the printing platen moves upwardly, moving the switch arm 163 into engagement with a fixed contact 165 , connected by wire $165a$ to the

fixed contact 161. The coil 152a of relay 152 is connected at one end to a plus power supply, and at the other end to the fixed contact 161. One end of each of the coils 166 and 167 of the counter relays M and M1 is connected to plus power supply. The other end of coil 166 is connected to a switch arm 168 normally in engagement with a fixed contact 169 and adapted to be moved out of engagement with respect to said contact, when the relay of counter M is energized. The switch arm 168 is connected by wire 168a, to spring finger 79d. The coil 167 for the relay of counter M1 is connected at its other end to a switch arm 170, and through wire 170a to spring finger 78d. The switch arm 170 is normally in engagement with a fixed contact 172, but is moved out of engagement with respect thereto upon energizing the relay for the counter M1.

Fixed contact 169 is connected by wire 169a to a fixed contact 174. In engagement with said fixed contact is a switch arm 175 connected by wire 175a to the fixed contact 159. On the counter wheel 142 or on the shaft therefor, is a projection or cam adapted to lift the switch arm 175 out of engagement with respect to the fixed contact 174 when said counter wheel is in initial position or in position to print zero. Fixed contact 172 is connected by wire 172a to a fixed contact 176. In engagement with said contact 176 is a switch arm 177 connected by wire 177a to fixed contact 160. On the counter wheel 143, or on the shaft therefor, is a pin or cam adapted to lift the switch arm 177 when said counter wheel is in initial position or in position for printing zero.

Spring finger 64 is connected to a plug power supply. Spring finger 65 is connected by wire 65a to spring finger 110. Spring finger 111 is connected by wire 111a to one terminal of the motor 85. The other terminal of the motor 85 is connected to minus power supply. Spring finger 107 is connected by wire 107a to spring finger 78c and to spring finger 79c.

The operation of the identifier will now be described:

The key is first inserted into the identifier causing spring finger 54 to move into engagement with spring finger 53 and out of engagement with respect to the spring finger 55. Upon turning the key, lever 57 drops permitting spring finger 64 to come into engagement with spring finger 65. Upon turning the key, furthermore, link 120 will be lowered causing return of the lever 123 to close the contacts of spring fingers 110 and 111. This action completes the circuit for the motor 85 which begins to operate to turn the shaft 91. As the sectors 78 and 79 come up, the switches 78c, 78d and 79c, 79d momentarily close a number of times depending upon the number of teeth passing the pawls 80a and 81a. Each time the spring fingers 78c and 78d close a circuit is completed through switch arm 153, fixed contact 154, wire 154a, spring fingers 106, 107, wire 107a, spring fingers 78c, 78d, wire 170a and coil 167, to energize the relay for the counter M1, moving the counter wheel 143 one digit. When the spring fingers 78c, 78d break contact, the counter relay is deenergized.

The same operation occurs for the counter M, upon opening and closing of the contacts 79c and 79d.

It will be noted that when the sectors 78 and 79 start coming back, the contacts 78c and 78d close, and the contacts 79c and 79d likewise close. However, before that occurs, the circuits for the

relays of the counters M and M1 are opened by cam 104 which moves the spring finger 106 out of engagement with the spring finger 107 and into engagement with the spring finger 108.

When the spring finger 106 moves out of engagement with the spring finger 107, the circuits for the counters are broken, but the engagement of the spring finger 106 with the spring finger 108 completes a circuit which causes a printing operation, as will now be described.

A circuit is first completed through the relay 147, through coil 148, switch arm 149, fixed contact 150, wire 150a, spring finger 108, spring finger 106, wire 154a, fixed contact 154, and switch arm 153. Energization of relay 147 causes switch arm 147a to move into engagement with the fixed contact 146 completing the circuit through the printing solenoid 140 causing the printing platen 141 to move upwardly to print against the counter wheels 142 and 143.

After the printing operation, the circuit for the printing solenoid is automatically released, as will now be explained.

Upward movement of the platen 141 moves

switch arm 163 into engagement with fixed contact 165, thus completing a circuit through minus power supply, switch arm 54, switch arm 53, wire 53a, switch arm 163, fixed contact 165, wire 165a, and coil 152a, thus energizing the relay 152. Energization of the relay 152 causes the switch arm 149 to move upwardly out of engagement with respect to the fixed contact 150 and into engagement with the fixed contact 151, thus breaking the circuit for the relay 147 which releases the

switch arm 147a which breaks the circuit for the printing solenoid 141 which causes the platen 141 to come down. Energization of the relay 152 causes the switch arms 155, 156 and 157 to move into engagement with the fixed contacts 159, 160 and 161, respectively. Relay 152 is held energized through the following circuit, coil 152a, fixed contact 161, switch arm 157, wire 53a, spring fingers 53 and 54. After the switch arm 163 is in engagement with the fixed contact 164, relay

152 is further held in energized condition through the following circuit, fixed contact 164, switch arm 163, wire 53a, switch arm 157, fixed contact 161 and coil 152a.

After the printing operation, the pulsing of the relays for the electro-magnets M and M1 continues until the counter wheels are zeroized, as will now be explained.

Considering first the counter M, while the relay 152 remains energized, a circuit will pass through switch arm 155, fixed contact 159, wire 175a, switch arm 175, fixed contact 174, wire 169a, fixed contact 169, switch arm 168 and coil 166 to energize the relay for said counter causing movement of the counter wheel 142 another digit. As soon as the relay for the counter M is energized however, switch arm 168 moves down to break the circuit for the relay. As soon as the relay becomes deenergized, arm 168 again moves up into engagement with fixed contact 169 to again close the circuit. In this manner, the wheel moves step by step to a zero position, in which position the switch arm 175 is raised to break the circuit for the relay and the counter wheel stops moving.

The counter M1 operates in the same manner to zeroize its counter wheel 143.

A second print will be obtained upon withdrawing the key. To withdraw the key, the same must first be turned to its initial angle, opening the spring fingers 64, 65. The key is then pulled out causing spring finger 54 to move out of en-

gagement with spring finger 53 and into engagement with spring finger 55, thus breaking one holding circuit for the relay 152. However, the relay 152 is held in energized condition through the second holding circuit passing through the switch arm 163, as hereinbefore described. A circuit is now completed through the relay 147 by reason of the contact of the spring finger 54 with the spring finger 55, and switch arm 149 with fixed contact 151. Energization of the relay 147 again pulls down switch arm 147 to close the printing circuit to cause another printing operation. As the platen 141 moves up, however, the second holding circuit for the relay 152 is broken to deenergize said relay.

Since the cam 104 has already rotated to a position when the spring finger 106 is out of engagement with the spring finger 108, the entire electrical system is back to normal condition.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. In combination, a key having a base part and another part, means for identifying the position of the other part of the key relative to the base part of the key, means to receive the key and position said base part of the key in a predetermined position, said key being rotatable in said key receiving means, a movable member, means for moving said movable member from an initial position into engagement with said other part of said key after the key has been positioned within said key receiving means and rotated therein, and means to pulse a number of pulsations corresponding to the extent of movement of said movable member.

2. In combination, a key having a base part and a movable part, means for identifying the position of the variable part of the key relative to the base part of the key, means to receive the key and position said base part of the key in a predetermined position, said key being rotatable in said key receiving means, a movable member, means for moving said movable member from an initial position into engagement with said variable part of said key after the key has been positioned within said key receiving means and rotated therein, means to pulse a number of pulsations corresponding to the extent of movement of said movable member, and means to return said movable member to initial position after the pulsing means have finished pulsing.

3. In combination, a key having a base part and a movable part, means for identifying the position of the variable part of the key relative to the base part of the key, means to receive the key and position said base part of the key in a predetermined position, said key being rotatable in said key receiving means, a movable member, means for moving said movable member from an initial position into engagement with said variable part of said key after the key has been positioned within said key receiving means and rotated therein, means to pulse a number of

pulsations corresponding to the extent of movement of said movable member, means to return said movable member to initial position after the pulsing means have finished pulsing, and means to disconnect the pulsing means from the movable member after the pulsing operation, to permit said movable member to be returned to initial position.

4. In combination, a key having a base part and another part, means for identifying the position of the other part of the key relative to the base part of the key, means to receive the key and position said base part of the key in a predetermined position, said key being rotatable in said key receiving means, a movable member, means for moving said movable member from an initial position into engagement with said other part of said key after the key has been positioned within said key receiving means, means to pulse a number of pulsations corresponding to the extent of movement of said movable member, said means for moving the movable member including an electric motor, and means responsive to the insertion and rotation of the key within said key receiving means to control the operation of the motor.

5. In combination, a key having a base part and another part, means for identifying the position of the other part of the key relative to the base part of the key, means to receive the key and position said base part of the key in a predetermined position, a movable member, means for moving said movable member from an initial position into engagement with said other part of said key after the key has been positioned within said key receiving means, means to pulse a number of pulsations corresponding to the extent of movement of said movable member, means to return said movable member to initial position after the pulsing means have finished pulsing, means to disconnect the pulsing means from the movable member after the pulsing operation, to permit said movable member to be returned to initial position, the means for moving the movable member comprising an electric motor, means to initiate the operation of the motor controlled by the positioning of the key within the key receiving means, and means to automatically stop the operation of the motor after the movable member has returned to its initial position.

6. In combination, a key having a base part and another part, means for identifying the position of the other part of the key relative to the base part of the key, means to receive the key and position said base part of the key in a predetermined position, a movable member, means for moving said movable member from an initial position into engagement with said other part of said key after the key has been positioned within said key receiving means, means to pulse a number of pulsations corresponding to the extent of movement of said movable member, said means for moving the movable member including an electric motor, means responsive to the positioning of the key within said key receiving means to control the operation of the motor, and means to deenergize the motor after said motor has run a predetermined number of revolutions.

7. In combination, a key, means to receive said key, a shaft, a member mounted for rotation about the axis of the shaft and adapted to be rotated into engagement with a portion of said key, a second shaft, a cam on said second shaft, a follower mounted for rotation about the axis of the first shaft and connected to said member

by a spring, said follower engaging said cam, means to retain said follower in engagement with said cam, and means cooperating with said member to produce a plurality of electric pulses depending upon the angle of rotation of said member.

8. In combination, a key, means to receive said key, a shaft, a member mounted for rotation about the axis of the shaft and adapted to be rotated into engagement with a portion of said key, a second shaft, a cam on said second shaft, a follower mounted for rotation about the axis of the first shaft and connected to said member by a spring, said follower engaging said cam, means to retain said follower in engagement with said cam, means cooperating with said member to produce a plurality of electric pulses depending upon the angle of rotation of said member, an electric motor, means connected with said motor for rotating said cam, and means rotatable with said cam about the axis of the second shaft, to control the operation of said motor.

9. In combination, a key, means to receive said key to be identified, a toothed member movable into engagement with a portion of said key, a switch, a member interposed between the switch and the teeth of said member, whereby as said toothed member is moved, the interposed member will pulse said switch a number of times depending upon the extent of movement of said member and hence corresponding to the position of said portion of the key, and means to move said interposed member out of engagement with respect to said toothed member.

10. In combination, a key, means to receive said key to be identified, a toothed member movable into engagement with a portion of said key, a switch, a member interposed between the switch and the teeth of said member, whereby as said toothed member is moved, the interposed member will pulse said switch a number of times depending upon the extent of movement of said member and hence corresponding to the position of said portion of the key, means to move said interposed member out of engagement with respect to said toothed member, an electric device connected by a circuit to said switch and responsive to the pulses from said switch, said interposed member being adapted to close said switch when it is moved out of engagement with respect to the toothed member, and means for opening said circuit before said interposed member is moved out of engagement with respect to said toothed member to close said switch.

11. In combination, a key, means to receive said key, a rotatable ratchet ring contained within said key receiving means and adapted to be rotated, upon rotating said key after the key is within said key receiving means, a pawl engaging said ratchet ring and permitting rotation of said ring in one direction, and adapted to prevent rotation of said ring in an opposite direction, until released from engagement with said ratchet ring, a pivoted latch, means on said ring to move said latch in one direction, upon rotating said ring from initial position, means to rotate said latch in an opposite direction, means on said latch to release said pawl from engagement with said ring, upon moving said latch in said opposite direction to permit rotation of said ring back to initial position.

12. In combination, a key, means to receive said key, a rotatable ratchet ring contained within said key receiving means and adapted to be rotated, upon rotating said key after the key

is within said key receiving means, a pawl engaging said ratchet ring and permitting rotation of said ring in one direction, and adapted to prevent rotation of said ring in an opposite direction, until released from engagement with said ratchet ring, a pivoted latch, means on said ring to move said latch in one direction, upon rotating said ring from initial position, means to rotate said latch in an opposite direction, means on said latch to release said pawl from engagement with said ring, upon moving said latch in said opposite direction to permit rotation of said ring back to initial position, a pulsing member movable into engagement with a key inserted into said key receiving means, an electric motor, means connected to said motor for moving said pulsing member, a switch controlling the operation of said motor, and means connected to said latch to control said switch.

13. In combination, a key, means to receive said key, a rotatable ratchet ring contained within said key receiving means and adapted to be rotated, upon rotating said key after the key is within said key receiving means, a pawl engaging said ratchet ring and permitting rotation of said ring in one direction, and adapted to prevent rotation of said ring in an opposite direction, until released from engagement with said ratchet ring, a pivoted latch, means on said ring to move said latch in one direction, upon rotating said ring from initial position, means to rotate said latch in an opposite direction, means on said latch to release said pawl from engagement with said ring, upon moving said latch in said opposite direction to permit rotation of said ring back to initial position, a pulsing member movable into engagement with a key inserted into said key receiving means, an electric motor, means connected to said motor for moving said pulsing member, a switch controlling the operation of said motor, means connected to said latch to control said switch, a second switch controlling the operation of said motor, and means controlled by said ratchet ring for opening and closing said second switch.

14. In combination, a key, means to receive said key inserted thereinto, said key being adapted to be rotated after the same is inserted into said key receiving means, means on said key receiving means adapted to be rotated by said key, when said key is rotated in one direction within said key receiving means, means to limit rotation of said rotatable member, means to lock said rotatable member against rotation in an opposite direction, a pulsing member movable into engagement with said key, an electric motor, means connected to said motor for moving said pulsing member, and means for simultaneously stopping the motor and releasing said rotatable member to permit said rotatable member to be moved back to initial position.

15. In combination, a key, means to receive said key inserted thereinto, said key being adapted to be rotated after the same is inserted into said key receiving means, means on said key receiving means adapted to be rotated by said key, when said key is rotated in one direction within said key receiving means, means to limit rotation of said rotatable member, means to lock said rotatable member against rotation in an opposite direction, a pulsing member movable into engagement with said key, an electric motor, means connected to said motor for moving said pulsing member, and means for simultaneously stopping the motor and releasing said ro-

tatable member to permit said rotatable member to be moved back to initial position, the motor circuit for said motor being controlled by said rotatable member.

16. In combination, a key, means to receive said key inserted thereinto, said key being adapted to be rotated after the same is inserted into said key receiving means, means on said key receiving means adapted to be rotated by said key, when said key is rotated in one direction within said key receiving means, means to limit rotation of said rotatable member, means to lock said rotatable member against rotation in an

opposite direction, a pulsing member movable into engagement with said key, an electric motor, means connected to said motor for moving said pulsing member, means for simultaneously stopping the motor and releasing said rotatable member to permit said rotatable member to be moved back to initial position, the motor circuit for said motor being controlled by said rotatable member, a pulsing circuit controlled by the pulsing member, and means controlled by movement of the motor to open the pulsing circuit.

BENJAMIN COOPER.
